(57) **CLAIM**

The ornamental design for a printer with exit tray, as shown and described.

DESCRIPTION

The design is embodied as a printer and particularly a thermal printer for printing color images. The printer includes an exit tray into which printed sheets of color images are collected.

FIG. 1 is a perspective view of the top, front and right side of the printer with exit tray showing our new design;

FIG. 2 is a perspective view of a bottom, rear and left side thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right side elevational view thereof; and,

FIG. 8 is a left side elevational view thereof.
